Christian W. Kragh

UNITED STATES PATENT OFFICE.

CHRISTIAN W. KRAGH, OF MADISON, WISCONSIN, ASSIGNOR TO THE NORTHERN ELECTRICAL MANUFACTURING COMPANY, OF SAME PLACE.

BRUSH-HOLDER FOR DYNAMO-ELECTRIC MACHINES.

SPECIFICATION forming part of Letters Patent No. 661,538, dated November 13, 1900.

Application filed September 11, 1899. Serial No. 730,059. (No model.)

To all whom it may concern:

Be it known that I, CHRISTIAN W. KRAGH, a citizen of the United States, residing at Madison, in the county of Dane and State of Wisconsin, have invented a certain new and useful Improvement in Brush-Holders for Dynamo-Electric Machines, of which the following is a specification.

My invention relates to brush-holders for dynamo-electric machines, and has for its object to provide a new and improved brush-holder of this description.

My invention is illustrated in the accompanying drawings, wherein—

Figure 1 is a side view of a brush-holder embodying my invention. Fig. 2 is a plan view of the device shown in Fig. 1. Fig. 3 is a sectional view of a part of the brush-holder attached to the stud or bolt by means of which the brush-holder is held in place.

Like letters refer to like parts throughout the several figures.

One of the objects of my invention is to provide a brush-holder which will elastically press the brush against the commutator.

The brush A, which makes contact with the commutator of the machine, may be made of any suitable material and is attached to the holding-piece B. The brush is preferably connected to the holding-piece in some suitable manner, so as to avoid a sliding contact. As illustrated in the drawings, two screws A' A' pass through the brush and clamp it firmly to the holding-piece B. I prefer to provide an outer conducting-piece A², the brush being securely clamped between this piece and the end of the holding-piece B, so as to insure a good electrical contact between the parts. The holding-piece B may be made of any desired form and, as herein shown, is provided at its end with two branches B' B', said branches being provided with openings for the supporting stud or bolt B². This bolt passes loosely through these openings, so that the holding-piece B is free to move about the bolt. Between the branches B' is an engaging part C, which engages the supporting-bolt B². This engaging part may be of any suitable construction and, as herein shown, 45 consists of a split collar, the split ends of

which are connected by means of a clamping-screw C', so that the engaging part may be rigidly clamped to the bolt B². It will be seen that by this construction the engaging part is adjustably clamped to its support. The holding-piece B is elastically connected to the engaging part C. Any suitable means for this purpose may be used. As herein illustrated, this elastic connection is made by the spring B³, which is attached at one end to the engaging part C, the other end engaging the holding-piece B. This spring passes between the branches B', as shown. In order to compensate for the relative movement of the holding-piece B and the engaging part C, I provide the spring B³ with a slot B⁴. The end of this spring presses upon the upper face of the holding-piece B, and a screw B⁵ connects the spring and the holding-piece B together. It will be seen that by this construction the spring and the holding-piece B are permitted to move relatively, the movement in one direction being limited by the engagement of the screw B⁵ with the inner end of the slot B⁴. It will also be seen that by this construction the brush is elastically pressed against the commutator and that the brush may be controlled by adjusting the position of the engaging part C. In order to do away with the sliding contact between the holding-piece B and the supporting stud or bolt B², I connect the engaging part C with the holding-piece B by means of the contact-spring C². Said contact-spring passes between the branches B' of the holding-piece, as shown, and has its end connected to a cross-piece B⁶, connecting said branches. This contact-spring permits the relative movement of the holding-piece B and the engaging part C, and yet provides a stationary contact between them.

In practice several of the brush-holders are generally connected to a single supporting-stud, and a series of these studs are used. It is of course evident that the brush may be used in any desired manner, and I do not limit myself in this particular. It will be seen that when several brush-holders are attached to a single supporting-stud any one of the brush-holders may be removed from the

commutator by unclamping the engaging part C and may then be moved to a position out of the way, so that any desired change or repair may be made while the machine is in 5 operation.

I have described in detail a particular construction embodying my invention; but it is of course evident that this construction may be varied in many particulars without 10 parting from the spirit of my invention, and I therefore do not limit myself to the construction shown.

I claim—

1. In a brush-holder for dynamo-electric machines, the combination of a holding-piece to which the brush is attached, a support upon which said holding-piece is movably mounted, a flat spring attached to said support and connected with said holding-piece 20 by a sliding contact and so as to elastically press the brush against the commutator, and a conductor fixedly attached to the support and to the holding-piece so as to give a fixed connection around the connection between 25 the support and holding-piece.

2. A brush-holder for dynamo-electric machines, comprising a holding-piece to which the brush is connected, said holding-piece

provided with two branches and movably mounted upon a support, an engaging part 30 between said branches, said engaging part securely attached to said support, a spring connected with said engaging part and passing up between the branches of the holding-piece, said spring engaging the holding-piece 35 on its upper face, so as to elastically press the brush against the commutator.

3. A brush-holder for dynamo-electric machines, comprising a holding-piece to which the brush is connected, said holding-piece 40 provided with two branches and movably mounted upon a support, an engaging part between said branches, said engaging part securely attached to said support, a spring connected with said engaging part and passing up between the branches of the holding-piece, said spring engaging the holding-piece 45 on its upper face, so as to elastically press the brush against the commutator, and a conductor fixedly attached at one end to the holding-piece and at the other end to the engaging part. 50

CHRISTIAN W. KRAGH.
